(57) **CLAIM**

The ornamental design for an electrical connector, as shown and described.

DESCRIPTION

FIG. 1 is a front, bottom and right-side perspective view of an electrical connector showing my new design;

FIG. 2 is a front, top and right-side perspective view thereof; FIG. 3 is a front, bottom and left-side perspective view thereof;

FIG. 4 is a rear, top and left-side perspective view thereof; FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof;

FIG. 10 is a bottom plan view thereof;

FIG. 11 is an enlarged view of the area 11 indicated by the double dot-dash broken lines in FIG. 1;

FIG. 12 is an enlarged view of the area 12 indicated by the double dot-dash broken lines in FIG. 2;

FIG. 13 is an enlarged view of the area 13 indicated by the double dot-dash broken lines in FIG. 3;

FIG. 14 is an enlarged view of the area 14 indicated by the double dot-dash broken lines in FIG. 4;

FIG. 15 is an enlarged cross-sectional view taken in the direction of line 15-15 in FIG. 5; and,

FIG. 16 is an enlarged cross-sectional view taken in the direction of line 16-16 in portion 15-15 in FIG. 5.

The evenly-spaced broken lines depict portions of the electrical connector that form no part of the claimed design. Also, the evenly-spaced broken lines in FIG. 15 and FIG. 16 depict the surfaces at the cut marks and form no part of the claimed design. The rectangle indicated by the double dot-dash broken lines shown in FIG. 1, FIG. 2, FIG. 3 and FIG. 4 illustrates the boundary of enlarged area of the design. The "11", "12", "13" and "14" indicia and splined curve indicated by the double dot-dash broken lines in FIG. 1, FIG. 2, FIG. 3 and FIG. 4 identify the enlarged area. None of the broken lines form any part of the claimed design. The single dot-dash broken lines define the boundary of the claimed design and form no part of the claimed design.
